UNITED STATES PATENT OFFICE.

AUGUSTIN J. CHEVRETTE, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

GIVEWAY FOR WEFT-REPLENISHING LOOMS.

Application filed July 30, 1925. Serial No. 47,145.

This invention relates to improvements in bobbin supports for weft replenishing mechanisms of the multi-color type and an object of the invention is to provide a support with a giveway the end of which may yield in any angular direction with respect to the supporting structure.

In replenishing mechanisms of the type referred to bobbins are released from one of several vertical compartments and guided along supports to transfer position just prior to the descent of the transerrer arm. It sometimes happens that the bobbin moves toward transfer position irregularly and is struck by the arm before being properly placed. When this occurs it is desirable that the support yield to prevent breakage and it is accordingly a further object of my invention to provide a support so constructed that it will yield downwardly under the pressure of an improperly placed bobbin. It also occasionally happens that a bobbin will be improperly transferred into a shuttle and as it is carried rearwardly by the lay will project to engage the giveway, and to prevent breakage under such conditions the support is so made as to yield upwardly or laterally when engaged by a misplaced bobbin.

A still further object of my invention is to provide a bobbin supporting unit symmetrical about the longitudinal axis thereof and having a supporting tubular section, a second tubular section yieldable relatively thereto, and a yieldable nose mounted on the second section, the nose yielding more easily than the second section.

With these and other objects in view which will appear as the description proceeds, my invention resides in the combination and arrangement of parts hereinafter described and set forth in the claims.

In the accompanying drawings wherein I have shown a convenient embodiment of my invention,

Fig. 1 is a vertical section through a multi-color weft replenishing mechanism looking toward the center of the loom and having my invention applied thereto,

Fig. 2 is an enlarged vertical section through the improved giveway,

Fig. 3 is an end elevation looking in the direction of arrow 3, Fig. 2,

Figs. 4 and 5 are transverse sections taken

on lines 4—4 and 5—5, respectively, of Fig. 2, and

Fig. 6 is an enlarged detail of the joint between the main body of the support and the yieldable tubular section on which the nose is mounted.

Referring more particularly to the drawings it will be seen that I have provided a weft replenishing frame 10 having a plurality of guideways 11 in which bobbins normally await transfer. The bobbins are delivered one at a time by devices not shown to move to transfer position under the transerrer arm 12. A guideway 13 is pivotally mounted at the bottom of a link 14 shown in dotted lines in Fig. 1 and loosely mounted on a fixed tie rod 15. The guideway 13 has a rearwardly and upwardly extending arm 16 which has pivotal connection as at 17 with a link 18 pivoted at 19 to some fixed part of the replenishing mechanism. A spring 20 serves to hold the guideway 13 in the position shown in Fig. 1. The matter thus far described is of common construction and for further description reference may be had to Patent No. 1,030,748 and Patent No. 1,366,950.

My invention relates more particularly to an improvement in a yielding support to lie under the yarn at the small end of the bobbin. As shown in Fig. 1 I provide a holder 30 which is secured to the tie rod 15 by means of set screw 31 said holder being split as at 32 to provide a clamp which may be tightened by screws 33. The support is formed of a tubular body 34 which is held in adjusted longitudinal position in support 30 by means of screws 33. A yielding second tubular section 35 substantially the same diameter as the body 34 is provided with a tapered connection with the body 34 as shown in Figs. 2 and 6. The tubular sections are held in substantial alignment by means of a coil spring 36 which fits snugly inside the sections, the rear end of the spring being bent as shown at 37 behind a shoulder 38 formed on the body 34. Similarly, section 35 is provided with a shoulder 39 which holds the projecting end 40 of the spring 36. In this way the coil spring is held in place under tension to keep the sections aligned and permit yielding of the section 35.

The outer end of the bobbin, when in

transfer position, rests on a solid nose 41 the forward end of which is rounded to permit easy movement of the bobbin thereacross and the rear end of which is provided with an eye 42 to receive the forward end of a light spring 43. The rear end of said spring 43 is received by a screw 44 adjustably threaded in a block 45 carried by the end of the body 34 and locked in position by nuts 46. Said member 41 is provided with a shoulder 47 which abuts the forward end of the section 35. The spring 43 lies inside the larger spring 36 without touching the same and yields more easily than spring 36.

Under normal transferring conditions the member 41 will be depressed about the lower portion of the shoulder 47 to assume the dotted line position 60 shown in Fig. 2. Should the member 41 be engaged by an improperly transferred bobbin as the latter moves rearwardly with the lay said member will be raised to the dotted line position 70 shown in Fig. 2. On the other hand if the bobbin is slow in descending to transfer position and is engaged by the transerrer arm 12 while still in contact with section 35, said section and member 41 will be moved to the dotted line position 80 shown in Fig. 2 and prevent breakage. It will be understood that the nose 41 engages the cylindrical portion of the yarn near the tip end of the bobbin, as set forth in Patent No. 1,518,392.

The support may be moved as a unit toward and from the bobbin by loosening the screws 33 and the angular adjustment may be secured by means of screw 31. By means of these two adjustments the position of the nose 41 may be varied as desired.

From the foregoing it will be seen that I have provided a jointed bobbin supporting unit for use in weft replenishing mechanisms symmetrical about the longitudinal axis thereof and having two yielding sections one of which yields more easily than the other and that said unit is mounted on a support which is angularly adjustable so that the nose 41 may be moved to any desired position.

Having thus described my invention it will be apparent that changes and modifications may be made therein by those skilled in the art without departing from the spirit and scope of the invention, and I do not wish to be limited to the details herein disclosed, but what I claim is:

1. In a weft replenishing mechanism for looms, a holder supported by the replenishing mechanism, and a bobbin support held by the holder and having two aligned yielding portions both positioned for engagement with the bobbin, one portion being yieldable more readily than the other portion.

2. In a weft replenishing mechanism for looms, a holder supported by and adjustable

with respect to the replenishing mechanism, and a bobbin support carried by the holder and having two yielding portions in alignment and spaced from the holder, the portion farther from the holder yielding more readily than the portion nearer the holder.

3. In a weft replenishing mechanism for looms, a pointed inclined bobbin support mounted on the replenishing mechanism and having independent aligned sections relatively movable with respect to each other, each section being angularly movable in all directions and said sections being yieldable under different degrees of pressure.

4. In a weft replenishing mechanism for looms, a bobbin support mounted on the replenishing mechanism and having a plurality of sections yieldable under different degrees of pressure and each movable in any angular direction with respect to the axis of the support.

5. A bobbin support for loom weft replenishing mechanism having a bobbin engaging portion movable in any angular direction with respect to the axis of the support and having a holding portion, the cross section of which is regular, whereby said bobbin support may assume a number of angular positions relatively to the bobbin, the axes of the two portions of the support being normally in substantial alignment.

6. A bobbin support for loom weft replenishing mechanism formed symmetrically about the axis thereof, and having a yielding bobbin engaging end portion the axis of which is parallel to the axis of the support, said end portion being movable in any angular direction with respect to the axis of the support.

7. A bobbin support for loom weft replenishing mechanism having a pair of aligned yielding bobbin engaging sections each of which is movable in any angular direction with respect to the axis of the support.

8. A bobbin support for loom weft replenishing mechanism having aligned yieldable bobbin engaging portions each of which is movable in any angular direction with respect to the axis of the support and one of said sections yielding more readily than the section adjacent thereto.

9. A bobbin support for loom weft replenishing mechanism comprising a hollow body portion, a hollow section resiliently held to the body portion, and a bobbin engaging end portion supported resiliently with respect to the support and hollow section by a spring passing through said body portion and hollow section.

10. A bobbin support for loom weft replenishing mechanism comprising a pair of tubular members movable with respect to each other, a coil spring located within said members and holding the same together

yieldably, and a bobbin engaging nose portion mounted yieldingly with respect to both of said members.

11. A bobbin support for loom weft replenishing mechanism comprising a hollow body portion, a bobbin engaging end portion movable in any angular direction with respect to the axis of the body portion, and a spring located in the hollow body portion and holding the end portion in yielding relationship with respect to the body portion.

12. A bobbin support for loom weft replenishing mechanism comprising a pair of tubular members, a coil spring located within 15 in said members and holding the same in alignment, a bobbin engaging end portion mounted for movement in any angular direction with respect to one of said tubular sections, and a second weaker spring located 20 within the first named spring to hold the bobbin engaging portion yieldingly in position.

13. In a weft replenishing mechanism for looms, a holder adjustable with respect to 25 the mechanism, and a bobbin support mounted on the holder and extending from the holder toward a bobbin when in transfer position, said support comprising a part fixed to the holder and another part aligning with 30 and yieldingly held to the fixed part and positioned to support a bobbin in transfer position and movable in all angular positions relatively to the first named part.

14. In a weft replenishing mechanism for 35 a loom, a holder normally fixed with respect to the mechanism, and a bobbin support held to the holder and movable relatively to the holder in a direction transverse to the axis of a bobbin in transfer position to assume any one of a number of adjusted positions 40 relatively to the holder, said support having a bobbin supporting end yieldable in all angular positions with respect to that part of the bobbin support which is held to the holder.

15. In a weft replenishing mechanism for 45 looms, a relatively fixed holder, and a bobbin support mounted on the holder, said support being movable longitudinally relatively to the holder in a direction toward and from a bobbin in transfer position to assume any one of a number of positions relatively to the holder and being also movable angularly to assume any one of a number of angular positions 50 relatively to the holder.

16. In a weft replenishing mechanism for 55 looms, a relatively fixed holder, and a bobbin support mounted on the holder, said support being movable longitudinally relatively to

the holder in a direction toward and from a 60 bobbin in transfer position to assume any one of a number of positions relatively to the holder and being also movable angularly to assume any one of a number of angular positions relatively to the holder, the end of 65 the support which supports the bobbin being yieldable in all angular directions relatively to the part of the support which is held to the holder.

17. In a weft replenishing mechanism for 70 looms, a holder, a bobbin support having a holding member held in the holder, a bobbin engaging tip member angularly movable with respect to the holding member, and resilient means connecting said members and 75 yielding to render the tip member capable of angular movement in any direction relatively to the holding member, the axes of said members being substantially parallel.

18. A bobbin support for a weft replenishing loom having a cylindrical holding part whereby the support may be held in a number of angular positions and said support also having a bobbin supporting end 80 yieldable in all directions relatively to the holding part, said parts having their axes 85 in substantial alignment.

19. A bobbin support for a loom weft replenishing mechanism comprising a body portion, a bobbin engaging portion separate 90 from the body portion, and a resilient device engaging both portions and holding them in normal position, said resilient device yielding to permit the bobbin engaging portion to move in any angular direction relatively 95 to the body portion.

20. In a weft replenishing mechanism for 100 looms, a bobbin support comprising a pair of members one of which is held rigidly with respect to the mechanism, and a resilient device interposed between said members and having holding contact therewith to afford a yielding mounting for one of said members thereby rendering possible yielding movement in all angular directions of one member 105 with respect to the other.

21. In a weft replenishing mechanism for 110 looms, a bobbin support comprising a pair of substantially cylindrical members one of which is held rigid with respect to the replenishing mechanism, a coil spring having the ends thereof in holding contact with said members, the other of said members being yieldable in all angular directions with respect to the first named member.

In testimony whereof I have hereunto affixed my signature.

AUGUSTIN J. CHEVRETTE.
